(57) **CLAIM**

The ornamental design for a rocker panel for a truck sleeper, as shown and described.

DESCRIPTION

FIG. 1 is a perspective view of a first embodiment of a rocker panel for a truck sleeper;
FIG. 2 is a front view thereof;
FIG. 3 is a left side view thereof;
FIG. 4 is a back view thereof;
FIG. 5 is a right side view thereof;
FIG. 6 is a top view thereof;
FIG. 7 is a bottom view thereof;

FIG. 8 is a reduced perspective view of our design; and,
FIG. 9 is a perspective view of a second embodiment of a rocker panel for a truck sleeper, whereas the second embodiment is a mirror symmetrical image of the first embodiment of FIGS. 1-8.

The broken line showing of a partial truck with sleeper, in FIG. 8, depicts environment and is not part of the claimed design.
